ELECTRICAL CONDENSER

Application filed May 10, 1929, Serial No. 362,055, and in Germany June 16, 1928.

This invention relates to electrical condensers comprising a number of condenser units arranged in series and mounted in a frame. Hitherto, in multiple condensers of this kind the connecting leads or conductors embedded in the individual condenser units were individually soldered to conductor wires secured to the frame. This method of mounting however exhibits the disadvantage that when replacing a damaged unit the soldered connection must in the first place be broken. In other arrangements, the condenser units are screw fastened between conducting carriers so that their removal or exchange may also be harmful.

These disadvantages are obviated in accordance with the present invention by the fact that the frame bars or rails of the condenser, upon which the condenser units are slidden by means of circuit connecting heads, are arranged so as to serve at the same time as carriers and bus-bars for the current so that the current can be conducted directly over said rails without special connectors, while the rails allow of easy removal of the units along them.

Soldering operations or the like are thus obviated, the units being simply slidden along current conveying rails with which they are directly in electrical contact.

In a particularly suitable construction these rails or bus-bars themselves constitute the cross struts of the frame of the condenser, whereby a considerable saving in material and weight is effected.

The circuit connecting heads of the condenser units consist advantageously of hollow sleeves which, beside their current conveying property, allow also internal cooling through the core of the units, by means of oil for example, when the whole condenser is immersed in an insulating oil bath.

With a condenser in which the units are mounted in said manner a damaged condenser unit can readily be removed from the frame and without any soldering being necessary, be replaced by a fresh unit. Further, the condenser units are by their metallic connecting heads directly in electrical contact with the carrying and current conveying

rails, so that there is no intermediate connecting member between the units and the rails or bus-bars in so far as said heads belong to the units themselves.

The invention will now be described, by way of example, with reference to the accompanying drawings, in which:

Figure 1 illustrates a constructional embodiment of the invention partly in side elevation and partly in longitudinal section;

Figure 2 is a partial front elevation thereof;

Figure 3 is a perspective view of the complete condenser arrangement.

In the constructional embodiment illustrated in the drawings each of the condenser units 7 (Figure 3) consists of spiral paper webs 3 wound on an insulating core 2, between which there are simultaneously wound up two metallic webs or foils 4, 4', so that the two foils 4, 4' which constitute the armatures of the condenser, are separated from each other by insulating material (paper) and have one edge in one of them projecting on one front side and the opposite edge in the other projecting on the other front side of the condenser beyond the paper webs 3 as shown in Figure 1 at the right and left hand of the condenser unit. Within the winding thus obtained there are inserted one or more pairs of thin connecting strips 5. While the same were individually soldered to conducting wires secured to the frame, according to the present invention they are conducted to metallic heads 8, which consist of hollow sleeves and are adapted to clamp the end or ends 6 of the strips 5. These metallic heads 8 are fastened by means of hollow bushings 9 within the insulating core 2 and carry two metal discs 10 for clamping fast the ends 6 of the strips 5 being inserted between them. Owing to the channel 9a in the heads 8, together with the bore of the central core 2, a good cooling of the condenser units from the inside is insured, especially when the condenser is immersed in an oil bath.

In the constructional embodiment illustrated in Figures 1 and 2 the connecting heads 8 of each unit 7 have rectangular transverse slots 11 therein by means of which the

units are slidden side by side over the carrying rails 12 of the condenser frame, which have a cross section corresponding to that of the slots 11 and constitute at the same time bus-bars for the current, being in direct electrical contact with the condenser heads 8. In the constructional embodiment illustrated in Figure 3, the rails or bus-bars 12 constitute at the same time the cross struts of the condenser frame and are secured to metallic rods 15^a, 15^b, 15^c, 15^a, which also belong to the condenser frame and the ends of which are attached to beams 16 of insulating material.

15 In this manner the bus-bars 12 arranged in vertical planes above one another are in direct electrical connection with one another, while the individual frame works constituted thereby are insulated from one another 20 by the beams 16. In the three-phase condenser illustrated by way of example in Figure 3, four such frame works are provided, the first and fourth of which are electrically connected together by the bridge piece 17 25 and by means of the terminal tag *a* are also adapted to be connected to the first phase of the electrical net-work; the two vertical pairs of rods of these two frame works are designated by 15^a. The frame work constituted by the vertical pair of rods 15^b and the bus-bars 12 connected thereto is adapted to be connected by means of the terminal tag *b* to the second phase of the net-work, while the rods 15^c together with the respective bus-bars are adapted to be connected by means of the terminal tag *c* with the third phase of the net-work.

30 In this manner there is associated a row of condenser units 7 to each phase of the net-work.

40 The bus-bars 12 and the slots 11 in which they are adapted to engage may be of any desired profile: for instance they may also be swallow-tailed, wedge-shaped, of conical or circular form and so on.

45 The form, construction and arrangement of each condenser unit may be varied as desired without exceeding the scope of the invention. Advantageously the units are immersed in a liquid dielectric such as oil.

50 What I claim is:

1. An electrical condenser comprising a frame, a number of condenser units, each having connecting leads and metallic head pieces at each end with means for fastening the connecting leads, rails on said frame for carrying the condenser units, constituting at the same time bus-bars for the current, and feather and groove connection means between said condenser unit head pieces and said bus-bars to allow the condenser units to be individually slidden on and off said bus-bars in electrical contact therewith.

55 2. An electrical condenser comprising a frame, a number of condenser units, each

having connecting leads and metallic head pieces at each end with means for fastening the connecting leads, rails arranged to constitute cross struts for said frame and to carry the condenser units, said rails constituting 70 at the same time bus-bars for the current, and the end head pieces of the condenser units being provided with a groove to engage over the longitudinal edge part of said bus-bars to allow the condenser units to be individually 75 slidden on and off said bus-bars in electrical contact therewith.

3. An electrical condenser comprising a frame, a number of condenser units, each having connecting leads and metallic head pieces 80 at each end with means for fastening the connecting leads, rails in the frame for carrying the condenser units, said rails constituting at the same time bus-bars for the current and being arranged in vertical rows, 85 upright conducting rods to carry the rails or bus-bars of each row, means for connecting said rods to the net-work, insulating cross beams to hold said upright rods in the frame, and feather and groove connection means between said condenser unit head pieces and said bus-bars to allow the condenser units to be individually slidden on and off said bus-bars in electrical contact therewith.

4. An electrical condenser comprising a 90 frame, a number of condenser units of the wound-up type, each having connecting leads and a central hollow core, hollow metallic head pieces on said core with clamp members for fastening the condenser unit connecting leads, rails on said frame for carrying the condenser units, constituting at the same time bus-bars for the current, said hollow head pieces of the condenser units being provided with a transverse groove to 100 engage over the longitudinal edge part of said bus-bars to allow the condenser units to be individually slidden on and off said bus-bars in electrical contact therewith.

5. In witness whereof I have hereunto signed 110 my name this 19th day of April, 1929.

EMIL HAEFELY.
